(57) **CLAIM**

The ornamental design for an electric drill driver, as shown and described.

DESCRIPTION

FIG. 1 is a perspective view of the design according to the invention.

FIG. 2 is a front view of the design according to the invention.

FIG. 3 is a rear view of the design according to the invention.

FIG. 4 is a top side view of the design according to the invention.

FIG. 5 is a bottom side view of the design according to the invention.

FIG. 6 is a right view of the design according to the invention.

FIG. 7 is a left view of the design according to the invention.

FIG. 8 is a perspective view of the design according to the invention in an alternate position; and,

FIG. 9 is a right side view of the design according to the invention in an alternate position.
